WITNESS:

John Lee Kirk INVENTOR
BY *Victor J. Evans* ATTORNEY

UNITED STATES PATENT OFFICE.

JOHN LEE KIRK, OF WAYNESBORO, PENNSYLVANIA.

POCKET.

1,423,434.

Specification of Letters Patent.

Patented July 18, 1922.

Application filed March 21, 1921. Serial No. 454,179.

To all whom it may concern:

Be it known that I, JOHN LEE KIRK, a citizen of the United States, residing at Waynesboro, in the county of Franklin and 5 State of Pennsylvania, have invented new and useful Improvements in Pockets, of which the following is a specification.

This invention relates to a pocket for garments, the general object of the invention 10 being to provide a pocket which may be easily and quickly placed in position in a garment the original pocket of which has become worn so that a person can repair his pocket without taking the garment to a 15 tailor.

Another object of the invention is to provide the pocket with a strip of adhesive so that the pocket can be connected with the garment very easily and quickly and without 20 sewing.

Another object of the invention is to make the pocket adjustable to fit different sizes of pocket openings in the garment.

This invention also consists in certain 25 other features of construction and in the combination and arrangement of the several parts, to be hereinafter fully described, illustrated in the accompanying drawings and specifically pointed out in the appended 30 claim.

In describing my invention in detail, reference will be had to the accompanying drawings wherein like characters denote like or corresponding parts throughout the 35 several views, and in which:—

Figure 1 is a fragmentary view showing my pocket attached to a garment.

Figure 2 is a view of the pocket itself.

Figure 3 is an end view looking into the 40 opening in the trousers pocket.

Figure 4 is a view of another style of pocket constructed in accordance with my invention.

As shown in these views the pocket 1 is 45 of the general shape of pockets used in garments. Figures 1, 2 and 3 show a pocket adapted to be placed at the sides of trousers while Figure 4 shows a pocket for an over-coat or coat and where the opening is at the 50 top. The pockets can be made of various shapes to suit the pockets in the garments for which they are to be substituted.

The pocket is made of any suitable mate-

rial, such as canvas and the like. Around the opening 2 in the pocket a band of adhesive 3 is placed so that the new pocket can be attached to the garment by moistening this band and pressing it by the hand or by an iron against the garment.

In order to make the pocket fit different 60 sizes of openings in garments I make the opening adjustable by forming a flap 5 at the top of the pocket which is adapted to fit in a small pocket 6 formed at the opposite side from the side forming the flap. 65 Thus by adjusting the extent to which the flap extends into the pocket 6 the sides of the opening 2 can be varied to suit the opening in the garment.

The pocket shown in Figures 1 and 2 has 70 its opening formed at the top of one side so that it can be placed in the worn pocket at the side of a pair of trousers. The pocket shown in Figure 4 has the opening at its top and is adapted to be placed in the pocket 75 of a coat or the like.

By my invention anyone can quickly and easily repair his pockets without going to a tailor and without sewing though the pocket can be sewed if desired. My pocket 80 can be removed from a garment when desired by simply moistening the adhesive strip to loosen the pocket from the garment.

My device can be placed inside of the old pocket or the old pocket can be cut out and 85 my pocket substituted.

It is thought from the foregoing description that the advantages and novel features of my invention will be readily apparent.

I desire it to be understood that I may 90 make changes in the construction and in the combination and arrangement of the several parts, provided that such changes fall within the scope of the appended claim.

What I claim is:—

A pocket for replacing a worn pocket of a garment having an opening therein and a strip of adhesive around the opening and means for adjusting the size of the opening, such means consisting of a flap formed of 100 one side of the pocket and a small pocket at the opposite side thereof for receiving the flap.

In testimony whereof I affix my signature.

JOHN LEE KIRK.
